(57) **CLAIM**

(21) Appl. No.: **29/236,472**

The ornamental design for device for detecting motion and
controlling light and temperature, as shown and described.

(22) Filed: **Aug. 15, 2005**

DESCRIPTION

(51) **LOC (8) Cl. 10-05**

FIG. 1 is a front view showing our new device for detecting
motion and controlling light and temperature design;

(52) **U.S. Cl. D10/106**

FIG. 2 is a rear view thereof;

(58) **Field of Classification Search** D10/106,

FIG. 3 is a bottom view thereof;

D10/46; 340/539.22-539.29, 540-567; 348/143,
348/155; 356/5.01, 140, 622; 362/802; 382/103

FIG. 4 is a top view thereof; and,

See application file for complete search history.

FIG. 5 is a side view thereof with the other side being a
mirror image.
